UNITED STATES PATENT OFFICE.

ROBERT SAYER ASPINWALL, OF DETROIT, MICHIGAN, ASSIGNOR TO LINCOLN MANUFACTURING COMPANY, OF DETROIT, MICHIGAN, A CORPORATION OF MICHIGAN.

DESIGN FOR AN ELECTRIC DROPLIGHT FIXTURE.

Application filed September 13, 1926. Serial No. 19,049. Term of patent 7 years.

To all whom it may concern:

Be it known that I, ROBERT SAYER ASPINWALL, a citizen of the United States, residing at Detroit, county of Wayne, State of Michigan, have invented a new, original, and ornamental Design for an Electric Drop-light Fixture, of which the following is a specification, reference being had to the accompanying drawings, forming part thereof.

Fig. 1 is a side elevation.

Figure 2 is a fragmentary bottom plan view of the article shown in Figure 1, and

Figure 3 is a fragmentary bottom plan view of the ceiling plate shown in Figure 1.

I claim:

The ornamental design for an electric drop-light fixture, as shown.

ROBERT SAYER ASPINWALL.
